[57] CLAIM

The ornamental design for a mobile workstation, as shown and described.

DESCRIPTION

FIG. 1 is a front left perspective view of a mobile workstation showing our new design;

FIG. 2 is a right side elevational view, the opposite side view being a mirror image thereof;

FIG. 3 is a top plan view thereof;

FIG. 4 is a front elevational view thereof;

FIG. 5 is a rear elevational view thereof; and

FIG. 6 is a bottom view thereof;

FIG. 7 is a front left perspective view of a second embodiment of a mobile workstation showing our new design;

FIG. 8 is a front elevational view thereof;

FIG. 9 is a right side elevational view, the opposite side view being a mirror image thereof;

FIG. 10 is a rear elevational view thereof; and

FIG. 11 is a top plan view, the bottom view being identical to FIG. 6;

FIG. 12 is a front left perspective view of a third embodiment of a mobile workstation showing our new design;

FIG. 13 is a front elevational view thereof; and,

FIG. 14 is a right side elevational view, the opposite side being a mirror image thereof.

The top view of the third embodiment is identical to FIG. 11, the bottom is identical to FIG. 6 and the rear view is similar to FIG. 10 with the uppermost surface elevated.
